UNITED STATES PATENT OFFICE

143,043

DESIGN FOR A WALL CABINET

Jacques Stanitz, Warren, Ohio, assignor to
Mullins Manufacturing Corporation, Salem,
Ohio, a corporation of New York

Application December 1, 1944, Serial No. 116,642

Term of patent 7 years

(Cl. D33—19)

To all whom it may concern:

Be it known that I, Jacques Stanitz, a citizen of the United States, residing at Warren, in the county of Trumbull and State of Ohio, have invented a new, original, and ornamental Design for a Wall Cabinet, of which the following is a specification, reference being had to the accompanying drawing, forming part thereof.

Figure 1 is a perspective view of a wall cabinet showing my new design; and Fig. 2 is a fragmentary side elevational view of a lower portion of the cabinet shown in Fig. 1. The rear and top portions, not shown in the drawing, are plain

flat surfaces and the other side is the same as illustrated.

The design is characterized by the offset relation between the lower front corner portion of the upper cabinet portion and the elliptically curved closure portion, all as shown. The essential features of my design are shown in full lines in the drawing.

I claim:

The ornamental design for a wall cabinet, substantially as shown and described.

JACQUES STANITZ.
